UNITED STATES PATENT OFFICE.

JOHN F. McMAHON, OF NEW YORK, N. Y., ASSIGNOR TO YELLOW TAXI CORP., OF NEW YORK, N. Y., A CORPORATION OF NEW YORK.

DESIGN FOR AN AUTOMOBILE BODY LAMP.

Application filed February 16, 1928. Serial No. 25,457. Term of patent 14 years.

To all whom it may concern:

Be it known that I, JOHN F. McMAHON, a citizen of the United States, residing at New York city, in the county and State of New York, have invented a new, original, and ornamental Design for Automobile Body Lamps, of which the following is a specification, reference being had to the accompanying drawing, forming part thereof, and in which—

I claim:

The ornamental design for an automobile body lamp as shown.

JOHN F. McMAHON,
